UNITED STATES PATENT OFFICE.

HUGH W. SANFORD, OF KNOXVILLE, TENNESSEE.

MINE CAR.

Application filed August 8, 1924. Serial No. 730,892.

To all whom it may concern:

Be it known that I, HUGH W. SANFORD, a citizen of the United States, residing at Knoxville, in the county of Knox and State of Tennessee, have invented a new and useful Improvement in Mine Cars, of which the following is a specification, reference being had to the accompanying drawing.

My improvement relates particularly to 10 the wheel and axle and axle bearing construction of mine cars.

The object of the invention is to provide a convenient and effective construction comprising axles and wheels and axle bearings 15 and means for engaging the axle bearings.

In the accompanying drawings—

Fig. 1 is a plan showing the under structure of a mine car embodying my improvement;

20 Fig. 2 is a perspective of one of the side angle plates which extend from axle to axle and form pedestals for the bearing boxes, parts being broken away;

25 Fig. 3 is an upright section in a plane along the axial line of one bearing and the adjacent wheel;

Fig. 4 is an upright section on the line, 4—4, of Figs. 1 and 3, looking toward the left;

30 Fig. 5 is an upright section on the line, 5—5, of Fig. 3, looking toward the right;

Fig. 6 is a horizontal section on the line, 6—6, of Fig. 4, looking upward;

35 Fig. 7 is an upright section on the line, 7—7, of Fig. 3, looking toward the left;

Fig. 8 is a section on the same line looking toward the right;

Fig. 9 is a horizontal detail section on the line, 9—9, of Fig. 3;

40 Fig. 10 is a plan of the axle box body;

Fig. 11 is a section similar to Fig. 3, the axle box and the wheel having exchanged places, the axle box being on the outer end of the axle;

45 Fig. 12 is an upright section on the line, 12—12, of Fig. 11, looking toward the right.

Referring to Figs. 1 to 10, inclusive, A, A are axles, B, B are wheels having hubs, B¹, 50 surrounding the axles. C, C are angle plates extending along the sides of the car frame and across the axles. Each such plate has a horizontal flange, C¹, bearing against the lower face of the wooden bottom flooring, D; and each such plate has a downward-directed flange, C², which is notched from below to

receive the axles. In the form shown in the drawings, the horizontal flange, C¹, is curved upward at C³ above each axle. The lower face of the wood bottom, D, is cut 60 away to make room for this upward extension of the angle plate. The purpose of this arrangement is to bring the car bottom lower than would otherwise be the case.

D¹ is a part of the upright side wall of 65 the car body. The body of the car may be of any desired construction, the wood bottom being secured in any desired manner, as by means of bolts, D², extending through said floor and the horizontal flange, C¹, of 70 the angle plate (Figs. 1 and 6).

The axle box body, E, surrounds the axle under the horizontal flange of the angle plate. Between its ends the upper face of said box has a transverse horizontal nearly 75 straight ridge or summit, E¹, resting against the lower face of the flange, C¹, of the angle plate. Said lower face is provided with a recess or groove, C⁴, in which the ridge, E¹, rests. Said ridge or summit is transverse 80 to the axle and forms a line on which the axle box may relatively rock on said flange of the angle plate, this feature contributing to making this a self aligning axle box such as is already known in this art. A strap or 85 stirrup, E², extends around the axle box and has its ends secured to the lower face of the flange, C¹, by means of bolts, E³. At each side of the upright part of the strap, the 90 axle box has a lug, E⁴, which, by engagement of the strap, limits endwise movement of the axle box. The upright parts of the strap come close to the sides of the axle box; but the lower part of the strap is curved 95 downward away from the lower face of the axle box, as shown in Figs. 3, 4, 5, 8, 11 and 12. Thus the strap allows some downward movement of the axle box relative to the car body. This is for the purpose of permitting the wheel to move downward 100 when the car is passing over a depression in the track at that side of the car. But such downward movement is at all times limited by the strap.

The rocking above mentioned is on a 105 nearly horizontal face and parallel to a plane which is upright and parallel to the car axle. The strap, E², also permits rocking of the axle box parallel to a horizontal plane.

110 The inner or right hand end of the axle box has an upright wall, E⁵, which fits

5 closely around the axle but permits free turning of the axle in the bearing. Within said end a channel, E⁶, is formed in the face of the wall which is next to the axle. This channel is to receive felt or other packing material adapted to prevent the passing of oil and dust or cinders.

10 The opposite or outer end of the axle box has no end wall formed integral with said box. A ring, E⁷, surrounds the axle and bears against the end of the box. The main part of said ring is in a plane transverse to the axle. Next to the axle said ring has a flange, E⁸, directed toward the opposite end 15 of the axle box. Said ring also has an outer flange, E⁹, which extends over a part of the outer face of the box. Parts, E¹⁰, of said flange are bent into a circumferential channel, E¹¹, formed on the outer face of the 20 axle box. By this means, said ring is removably secured to the axle box.

25 In the space around the axle and within the axle box are anti-friction rollers, F, placed parallel to the axle and having at each end a small journal, F¹. At the outer end of the bearing the flange, E⁸, of the ring, E⁷, prevents the rollers, F, from moving out of position by movement toward the axis of the bearing, when the bearing is 30 removed from the axle. At the opposite or inner end of the bearing, a retaining ring, F², surrounds the axle and extends between the axle and the adjacent journals, F¹, said ring being so proportioned as to preclude 35 movement of the journals, F¹, toward the bearing axis for the dislodging of the rollers when the bearing has been removed from the axle.

40 A second ring, G, is placed against and secured to the outer face of the upright part of the ring, E⁷. Said ring, G, has a flange, G¹, directed toward the hub, B¹, of the wheel and fitted closely to the axle to prevent flow of lubricant out of the bearing box 45 along the face of the axle.

45 Between the inner end of the wheel hub and the outer face of the upright flange of the angle plate is placed the removable thrust wall, H, surrounding the axle. The thrust wall, H, has an inner face adapted to over-lap and bear closely against said flange, C², of the angle plate.

50 Between the wall, H, and the adjacent end of the wheel hub any desired number of washers, H¹, surround the axle. The wall, H, has a flange, H², approximately concentric to the axle and extending outward over the washer or washers, H¹, and around the adjacent end of the hub, the diameter of said flange being sufficient to leave an annular space between the flange and said washers and the adjacent outer face of the hub to receive packing to prevent the passing of dust and cinders and to hold grease and other lubricant. Said wall also has an an-

50 nular flange, H³, extending into the opening in the flange, C², of the angle plate and surrounding a part of the flange, G¹, which, as above described, fits closely around the axle. (Figs. 3, 8, 11 and 12.)

55 It will now be seen that wheel thrust parallel to the axle and toward the car body will be taken by the thrust wall, H, and transmitted by the latter to the upright flange, C², of the angle plate, C. Thus the bearing box is left free or "floating" on the axle and is entirely free to take the rocking movements above described and to move endwise to the extent permitted by the angle plate flange, C², and by the lugs, E⁴, and by 60 the collar, A¹, on the axle at the inner end of the axle box. (Figs. 3, 8, 11 and 12.) Said collar may be omitted.

65 The outer end of the hub, B¹, has two diametrically opposite notches, B², which are adapted to be brought into alignment with the transverse axle aperture, A², for receiving a cotter pin, A³, which will serve to prevent rotation of the wheel independently 70 of the axle, whereby the wheel is made "fast". Next to the outer end of the hub, a sleeve, A⁴, surrounds the axle and is secured thereto by a transverse cotter pin, A⁵. This sleeve, A⁴, bears against the adjacent end of the hub. When the wheel is to be "loose", 75 the cotter pin, A³, is removed.

80 When an axle and its wheels and its axle boxes are to be removed from the car, the straps or stirrups, E², are released from the bolts, E⁶. Then that end of the car is lifted 85 by means of a lifting jack or lever, the axle and its wheels and axle boxes remaining at rest, the axle and the flange, H³, of the thrust wall, H, moving downward, relatively, out of the notch formed in the upright flange, 90 C², of the angle plate, C.

95 The wheel, B, is chambered at B⁵ to receive lubricant. Adjacent each wheel, B, a pipe, I, for carrying lubricant into the axle box, extends loosely through an orifice, 100 C⁵, of the adjacent angle plate flange, C², toward the opposite angle plate member until nearly the middle transverse upright plane of the axle box is reached and then turns toward and into the axle box, said pipe 105 being threaded or otherwise well secured in the wall of the axle box. On the outer end of the pipe, I, is fitted any suitable device 110 adapted for receiving and transmitting lubricant into said pipe. This may be a nipple or screw plug, I¹, of well-known form for connection with a grease gun. The orifice, C⁵, is to be large enough to allow the pipe, I, to move to the extent demanded by the rocking or other shifting of the free or 115 "floating" axle box; and said orifice is to be far enough away from the adjacent axle to bring the end of said pipe out of the range of the adjacent wheel, B, in order that lubricant may be injected into the axle box with- 120

out passing between spokes or other openings in the wheel and without the necessity of turning the wheel into any particular position on the axle. This provision will be 5 a matter of much convenience in the operation of such cars. At any time when the car is stationary, lubricant may quickly be injected into the four axle boxes without regard to the positions of the wheels on their 10 axles.

Turning now to Figs. 11 and 12, the axle box, E, surrounds the end of the axle, A, and the angle plate, C, is reversed so as to bring its downward-directed flange, C², to the inner part of said plate, and the wheel, B, surrounds the axle opposite the inner end of the axle box; the flange, C², extending between said box and said wheel. The wheel hub, B¹, extends inward across 20 the collar, A¹, and said end of the hub is provided with two diametrically opposite notches, B³, which are adapted to be brought into alignment with the transverse axle aperture, A⁶, for receiving a cotter pin, B⁴. 25 When the cotter pin is in position, the wheel, B, is fixed on the axle, and when the cotter pin has been removed, the wheel is loose on the axle.

The thrust wall, H, is placed between the hub, B¹, and the angle plate flange, C², as in the preceding figures of the drawings. The strap or stirrup, E², and the lugs, E⁵, are present as before. The rings, E⁷ and G are present as before. The outer end of the 30 axle box extends across the end of the axle and presents an end wall, E¹², surrounded by an annular channel or recess, E¹³, which receives the journals, F¹, of the rolls, F. An oil plug, E¹⁴, is tapped into the wall, E¹², to 40 form a port for the admission of lubricating oil or grease. The wheel, B, is chambered for oiling as in Fig. 3 of the drawings; but this chambering is not shown in Fig. 11.

I claim as my invention—

45 1. In a railway car, the combination with an axle and a wheel surrounding the axle, of a horizontal angle plate extending above and crosswise of the axle and having an upper horizontal flange and a notched downward-directed flange, an axle box surrounding the axle under the horizontal flange of the angle plate and bearing against said notched flange, and means for holding the axle box in relation to said angle plate horizontal flange, substantially as described.

50 2. In a railway car, the combination with an axle and a wheel surrounding the axle, of a horizontal angle plate extending above and crosswise of the axle and having an upper horizontal flange and a notched downward-directed flange, an axle box surrounding the axle under the horizontal flange of the angle plate and bearing against said flange, means for holding the axle box in relation to said angle plate horizontal flange,

and a thrust wall between the wheel and the downward-directed flange, substantially as described.

3. In a railway car, the combination with an axle and a wheel surrounding the axle, and an axle box surrounding the axle near the wheel, of a horizontal angle plate extending above and crosswise of the axle and having an upper horizontal flange extending over the axle box and said plate having a 70 notched downward-directed flange extending between the wheel and the axle box, and means for holding the axle box in relation to said angle plate horizontal flange, substantially as described. 75

4. In a railway car, the combination with an axle and a wheel surrounding the axle and an axle box surrounding the axle near the wheel, of a horizontal angle plate extending above and crosswise of the axle 80 and having an upper horizontal flange extending over the axle box and said plate having a notched downward-directed flange extending between the wheel and the axle box, means for holding the axle box in relation to said angle plate horizontal flange, and a thrust wall between the wheel and the downward-directed flange, substantially as described. 85

5. In a railway car, the combination with 90 two parallel axles, a wheel surrounding one of said axles and a wheel surrounding the other of said axles, and an axle box surrounding each of said axles near said wheels, of a horizontal angle plate extending above and across said two axles and having an upper horizontal flange resting on said axle boxes, and means for holding the axle boxes in relation to said angle plate horizontal flange, substantially as described. 100

6. In a railway car, the combination with two parallel axles, a wheel surrounding one of said axles and a wheel surrounding the other of said axles, and an axle box surrounding each of said axles near said wheels, of a horizontal angle plate extending above and across said two axles and having an upper horizontal flange resting on said axle boxes, and said angle plate having a notched downward-directed flange extending between said hubs and said axle boxes and being notched to receive the axles, means for holding the axle boxes in relation to said angle plate horizontal flange, and thrust walls between the wheels and the 110 downward-directed flange, substantially as described. 115

7. In a railway car, the combination with two parallel axles, a wheel surrounding one of said axles and a wheel surrounding the other of said axles, and an axle box surrounding each of said axles near said wheels, of a horizontal angle plate extending above and across said two axles and having an upper horizontal flange resting on 120 125 130

of a horizontal angle plate extending above and crosswise of the axle and having an upper horizontal flange and a notched downward-directed flange, a thrust wall bearing 5 against the outer face of said downward-directed flange and having an outward-directed flange surrounding the hub of the wheel, an axle box surrounding the axle under the horizontal flange of the angle 10 plate and bearing against said flange, and detachable means for holding the axle box in relation to said angle plate horizontal flange, substantially as described.

17. In a railway car, the combination with 15 an axle and a wheel surrounding the axle, of a horizontal angle plate extending above and crosswise of the axle and having an upper horizontal flange and a notched downward-directed flange, a thrust wall bearing against 20 the outer face of said downward-directed flange and having a flange extending into said downward-directed flange, an axle box surrounding the axle under the horizontal flange of the angle plate and bearing against 25 said flange, and detachable means for holding the axle box in relation to said angle plate horizontal flange, substantially as described.

18. In a railway car, the combination with 30 an axle, a wheel surrounding the axle, of a horizontal angle plate extending above and crosswise of the axle and having an upper horizontal flange and a notched downward-directed flange, a thrust wall bearing against 35 the outer face of said downward-directed flange and having a flange extending into the angle plate downward-directed flange and having an outward-directed flange surrounding the hub of the wheel, an axle box 40 surrounding the axle under the horizontal flange of the angle plate and bearing against said flange, and detachable means for holding the axle box in relation to said angle plate horizontal flange, substantially as described.

19. In a railway car, the combination with 45 an axle and a wheel surrounding the axle, of a horizontal angle plate extending above and crosswise of the axle and having an upper horizontal flange and a notched downward-directed flange, a thrust wall bearing against the outer face of said downward-directed flange, an axle box surrounding the axle and having an upper transverse ridge bearing 50 against the angle plate horizontal flange, and means for holding the axle box in relation to said angle plate horizontal flange, substantially as described.

20. In a railway car, the combination 55 with an axle and a wheel surrounding the axle, of a horizontal angle plate extending above and crosswise of the axle and having an upper horizontal flange and a notched downward-directed flange, a thrust wall bearing 60 against the outer face of said down-

ward-directed flange and having an outward-directed flange surrounding the hub of the wheel, an axle box surrounding the axle and having an upper transverse ridge bearing against the angle plate horizontal flange, and means for holding the axle box 70 in relation to said horizontal flange, substantially as described.

21. In a railway car, the combination with an axle and a wheel surrounding the axle, of an angle plate extending parallel to the length of the car and having an upper horizontal flange and a notched downward-directed flange, a thrust wall bearing 75 against the outer face of said downward-directed flange, an axle box surrounding the axle under said horizontal flange and bearing against said flange, and means for holding the axle box for limited endwise movement and for limited downward movement, 80 substantially as described.

22. In a railway car, the combination with an axle and a wheel surrounding the axle, of an angle plate extending parallel to the length of the car and having an upper horizontal flange curved upward above the axle and having a notched downward-directed flange, an axle box surrounding 90 the axle under the horizontal flange of the angle plate and bearing against said flange, and means for holding the axle box in relation to said angle plate horizontal flange, 95 substantially as described.

23. In a railway car, the combination with an axle and a wheel surrounding the axle, of a wooden bottom, an angle plate extending under the wooden floor and parallel to the length of the car and having an upper horizontal flange curved upward above the axle and having a notched downward-directed flange, an axle box surrounding 100 the axle under the horizontal flange of the angle plate and bearing against said flange, and means for holding the axle box in relation to said angle plate horizontal flange, 105 substantially as described.

24. In a railway car, the combination with an axle and a wheel surrounding the axle, of a wooden floor, an angle plate extending under the wooden floor and parallel to the length of the car and having an upper horizontal flange and a notched downward-directed flange, a thrust wall bearing against the outer face of said downward-directed flange, an axle box surrounding the axle under said horizontal flange and bearing 115 against said flange, and means for holding the axle box substantially against endwise movement and for limited downward movement, substantially as described.

25. In a railway car, the combination with an axle and a wheel surrounding the axle, of a wooden floor, an angle plate extending under the wooden floor and parallel to the length of the car and having an up- 120

6

per horizontal flange bolted to the wooden floor and having a notched downward-directed flange, a thrust wall bearing against the outer face of said downward-directed flange, an axle box surrounding the axle and having an upper transverse ridge bearing against the angle plate horizontal flange, and means for holding the axle box in relation to said angle plate horizontal flange, 10 substantially as described.

26. In a railway car, the combination with an axle and a wheel surrounding the axle, of a wooden floor, an angle plate extending under the wooden floor and parallel to the length of the car and having an upper horizontal flange and a notched downward-directed flange, an axle box surrounding the axle and bearing against the angle plate horizontal flange and having lateral lugs, 15 20 lugs, a strap placed in relation to said lugs, and bolts extending through said horizontal flange and said strap, substantially as described.

tal flange and said strap, substantially as described.

27. In a railway car, the combination with an axle and a wheel surrounding the axle, of a wooden floor, an angle plate extending under the wooden floor and parallel to the length of the car and having an upper horizontal flange and a notched downward-directed flange, a thrust wall bearing against the outer face of said downward-directed flange, an axle box surrounding the axle and bearing against the angle plate horizontal flange and having lateral lugs, a strap placed in relation to said lugs, and bolts extending through said horizontal flange and said strap, substantially as described. 25 30 35

In testimony whereof I have signed my name, this 30th day of July, in the year one thousand nine hundred and twenty-four. 40

HUGH W. SANFORD.
